ATTORNEY.

UNITED STATES PATENT OFFICE

HORACE M. WOOLLEY, JR., OF SAN FRANCISCO, CALIFORNIA

HANGER FOR CONCRETE CONSTRUCTION FORMS

Application filed September 24, 1928. Serial No. 307,836.

This invention relates to improvements in hangers for forms employed in the support of concrete floors during their formation or pouring.

5 The objects of this invention are the provision of cheaply constructed cooperating parts adapted for ready assembly with the supporting beam and soffit forms to provide, without the usual maze of loose wires, a 10 strong supporting frame for the floor slab of a concrete floor structure; to provide parts which are capable of easy separation when it is desired to remove the soffit forms after the floor structure has set; to provide a spacer 15 bracket, its use ensuring a uniform space between the supporting beam flange and the soffit form surface, it further affording a lock means for precluding the rotation of the hanger bracket nut, after the latter is once 20 set; to provide an improved form of soffit form support, the construction of which overcomes the necessity of drilling bolt apertures, and which is adapted for use in each assembly and removed therefrom on the disassembly 25 of the parts after the floor has set; and to provide a means for precluding the hanger brackets from spreading from their position of normal holding relation.

With the above mentioned and other objects in view, the invention consists in the novel construction and combination of parts hereinafter described, illustrated in the accompanying drawings and pointed out in the claims hereto appended; it being understood 35 that various changes in the form, proportion, size and minor details of construction within the scope of the claims may be resorted to without departing from the spirit or sacrificing any of the advantages of the invention.

40 To more fully comprehend the invention, reference is directed to the accompanying drawings, wherein:—

Fig. 1 is a view in transverse vertical section of a portion of a supporting beam with the preferred embodiment of my invention assembled to suspend the soffit boards beneath the beam.

45 Fig. 2 is a section on line 2—2 of Fig. 1.
50 Fig. 3 is a view in plan of the disclosure

in Fig. 1 with both hanger bracket nut locks in operative position.

Referring to the several views of the drawings wherein like characters of reference designate corresponding parts, 1 indicates a supporting I-beam. 2 are the soffit boards suspended beneath the I-beam in a hereinafter described manner for supporting the concrete mix until the same sets forming a floor. Extending transversely beneath the soffit boards, 55 at right angles to the I-beam is a soffit cleat 3, consisting of a pair of angle members 4 disposed with opposing faces of corresponding members in parallel spaced relation affording a slot 5 therebetween. The members are held in cooperating relation by fastening means 6 which mount between the opposing faces spacer washers 7, ensuring the uniformity of slot 5 throughout the length of members 4. Members 4 are detachably secured to the under faces of soffit boards 2 by nails or other fastening devices 8. Spacer brackets 8 are disposed in parallel end to end alignment on the upper surface of the soffit boards 10 overlying the soffit cleat 3, and are positioned with their opposing ends in spaced relation. Spacer brackets 8 are of channel construction with the upper flange 9 contacting with the underside of the I-beam flange near one edge and the lower flange 10 resting on the upper surface of a soffit board to which it is secured by attaching means such as nails 11 passing through openings in the flange. The top and bottom flanges 9 and 10 are provided with aligned apertures through 80 which extend the respective shanks 12 and 13 of the hanger bracket nut 14 and the hanger bracket bolt 15, the latter also passing through bored holes in the soffit boards 2. When assembled and extending toward each other through the spacer bracket flange openings, and with the shank of bolt 15 extending through slot 5 the shanks are in threaded 85 relation to enable the curved upper supporting end 16 of nut 14 to be drawn tightly onto the surface of I beam flange with the head of the bolt 15 bearing tightly against the edge of the soffit cleat slot.

To lock the nut 14 from rotating, the upper flanges 9 are severed for a portion of the 90 95 100

length from the brackets 8 and said severed portions are longitudinally slotted providing fingers 17 bendable upwardly one to lie on each side of the supporting end 16 as in the drawings. The spacer brackets 8 are perforated at 18 to admit of the concrete passing therethrough and creating a bond therewith.

It will be observed that with the floor supporting form hung in the manner illustrated and described that the concrete will be adequately supported during its laying, tamping and curing. When the floor has set, the bolts 15 are unthreaded from their nuts 14 which releases the hanger brackets 4 for stripping from the soffit boards, and the soffit boards 2 in turn from the under surface of the floor. Brackets 8 and nuts 14 remain imbedded in the floor and the ends of nails 11 projecting from the floor may be clipped off.

The spacer brackets 8 are of a dimension that the outer ends thereof, when the bracket is properly hung, lies a distance from the I-beam to enable the end of the spacer to be used as a stop.

25 I claim:—

1. A hanger for concrete construction forms, comprising a flanged spacer bracket provided with aligned apertures through its flanges and having finger portions formed by a longitudinal slot in one flange, and a hanger bracket for reception within said aligned apertures, said finger portions being adapted to fixedly position the hanger bracket.

2. A hanger for concrete construction forms comprising a spacer bracket provided with parallel flanges extending laterally therefrom, one of said flanges being free from the body for a portion of its length and provided with an aperture, and the free portion being slotted inwardly from its end providing spaced fingers, a hanger bracket extending through the flange aperture, said fingers adapted for bending to lie one at each side of said hanger bracket.

45 3. A hanger for concrete construction forms, comprising a flanged spacer bracket for positioning with a web portion thereof vertically disposed, said spacer provided at an edge thereof with a horizontal flange having an aperture therethrough, a hanger bracket for reception within said aperture, said spacer bracket being provided with finger members adapted for fixedly positioning the hanger member.

55 In testimony whereof I have signed my name to this specification.

HORACE M. WOOLLEY, JR.
